DELAY ACTION MECHANISM FOR SNAP SWITCHES

Ewing L. Sharp, Hollywood, Calif., assignor to
Victory Switch Co., Hollywood, Calif.

Application October 28, 1941, Serial No. 416,838

13 Claims. (Cl. 200—34)

The present invention relates to improvements in electrical switches and more particularly to snap switches having an optional delay action mechanism which, upon the completion of the delay function automatically restores the switch to a snap action movement.

This invention further relates to certain improvements in both the snap and delay action mechanism set forth in my copending application entitled Delayed action mechanism for snap switches, Ser. No. 312,011, filed January 2, 1940, which matured into Patent #2,261,189, November 4, 1941, the present application being a continuation in part of said earlier application.

Among the more important objects of the invention are: to provide improved circuit opening and closing means for the switch; to provide improved mounting means for the circuit opening and closing means; to provide means for yieldably acting upon certain movable means to make the delay action feature of the switch mechanism more positive.

Speaking more specifically, further important objects are: to provide improved means for making the piston stem mechanism more sturdy and leak proof; to improve upon the cradle mechanism and dashpot operating mechanism in such a manner that their assembling is facilitated and their parts are simplified so as to create a more positive, inexpensive and dependable construction; to improve upon the brush breaker whereby, whether it is in the open or closed position, it will act as its own spark snuffer, because it shields one contact from the other at all times.

With the foregoing and other objects in view, the invention resides in the novel arrangement and combination of parts and in the details of construction hereinafter described and claimed, it being understood that changes in the precise embodiment of the invention herein disclosed may be made within the scope of that which is claimed, without departing from the spirit of the invention.

Referring to the drawings wherein is shown a preferred embodiment of the invention together with an alternate embodiment of one of the switch parts,

Fig. 1 is a vertical mid section showing the switch "on" or in circuit closing position, the delay action mechanism having remained passive during the conventional manual snap action closing movement of the switch lever. In the view the broken line indication of the switch lever indicates a position thereof resulting from

another conventional manual snap action movement.

Fig. 2 is a view taken on the plane indicated by the line 2—2 of Fig. 1, a side portion of the switch lever being broken away.

Fig. 3 is a vertical section taken on line 3—3 of Fig. 2.

Fig. 4 is a transverse section taken on line 4—4 of Fig. 2 with certain interior parts omitted.

10 Fig. 5 is a fragmentary transverse section taken on line 5—5 of Fig. 2 with certain interior parts removed.

Fig. 6 is a fragmentary vertical section taken on line 6—6 of Fig. 3, the dashpot cylinder being 15 omitted.

Fig. 7 is a fragmentary perspective view on a larger scale of some of the parts comprising the delay action mechanism which controls the delayed action of the switch.

20 Fig. 8 is a perspective view on a larger scale of the circuit maker and breaker dissociated from the cradle which actuates the same.

Fig. 9 is a plan view showing the cradle, circuit maker and breaker and piston stem operatively 25 related, and,

Fig. 10 is a perspective view showing per se an alternate embodiment of the breaker and brush shown in Fig. 8.

Referring in detail to the drawings, therein is 30 shown an open faced, opened bottom switch casting 1 constructed from Bakelite or other suitable insulating material and provided with a top wall 2, side walls 3 and 4 and a back wall 5. A cross wall 6, having a horizontally directed flange 7 and a vertically directed depending flange 8, bridges the gap between the side walls 3 and 4 at their lower front ends. The vertical outer face of the flange 3 lies in the same plane as the front edges of the top wall 2 and the side 35 walls 3 and 4, and the horizontal top face of the flange 7 lies in a plane flush with the bottom edge of the back wall 5.

In the back wall 5 slightly above its lower edge is formed a transversely extending channel 45 9 paralleling the wall's lower edge to form a seat for the flange 10 of the dashpot 11. Said back wall, on a line with the face forming the top wall of the channel 9, is thickened to provide a cam shaped swell 12 the function of which will 50 be explained later.

The dashpot 11 has its front face thickened at 13 and provided with a protruding lip 14 to form a ledge engageable on its underside by a set screw 15 which extends through the face strap 55 15a and with a screw threaded relation through

the aforesaid flange 3 to maintain a rigid support of the dashpot against the lower edges of the side walls, there being a clearance space between the lip 14 and rear face of the flange 3 to provide for the upswinging of the dashpot into position when the same is gyrated about said channel 9 as an axis.

The dashpot 11 further comprises a cylinder 16 having its upper end open and bottom end closed. The closed end of the cylinder is provided with an internally threaded bore into which is screwed a valve in the form of a screw 17 and washer 18 for controlling the influx and efflux of air to and from the cylinder.

A piston 19 operates in the cylinder 16, said piston being provided with an operating stem 20. In Fig. 7 it will be seen the piston consists of a cupshaped, flexible gasket washer 21 which is interposed between two flat disks 22 and 23. Said disks together with the washer are provided with elongated slots at their centers and through said slots is extended a tongue 24 with which the piston stem is provided, said tongue being peened over the bottom disk 23 to grip the piston assembly combination as a whole, the metal of the tongue being soft enough so that in the peening operation it is squeezed sufficiently in the aperture or slots of the disks to make a leak proof joint.

The piston stem 20 is shown as being constructed from a flat metal sheet and having a cutout through its mid section, said cutout having an arclike curvature 25 forming one of its boundaries, and there is a gap 26 in the side of the stem which is opposite said curvature. In the front side of the upper end portion of said cutout is an offset recess or seat 27, the function of which, as well as that of the arclike curvature 25 and the gap 26 will be explained later.

Wall 3 of the casing, as shown in Fig. 6, is provided with a longitudinally directed guideway or trapezoidal shaped groove 28 extending along the inner face of said wall a short distance from the back wall 5 as seen in Fig. 3 and having the contracted mouth of the groove or the shorter parallel side forming the trapezoidal groove flush with the inmost face of the wall 3.

Into the acute angles of the trapezoidal groove are sprung the obtusely directed edge flanges 29 and 30 of the fulcrum yoke 31 which pivotally supports the two types of breakers 32 and 32a shown in Figs. 8 and 10.

Said yoke 31 is bent upon itself to form a flange 33 thereby to provide a pair of jaws or arms wherebetween the breaker is pivotally mounted, there being an aperture or pivot hole 34 in the breaker 32 and an aperture 34a in the breaker 32a in which seats the boss 35 projecting from the inner face of the flange 33 into the opening formed by said jaws. Said boss serves the purpose of an axle and eliminates a costly assembling job.

The breaker 32 or brush carrying member is desirably made of non-conductor, fibrous material and carries a brush 36, in the form of a rivet extending therethrough, through which the current flows when the brush has been moved from the circuit opening position shown in phantom lines in Fig. 3 to circuit closing position with its contacts 37 and 38 shown in Figs. 2, 4 and 8. In said figures it will be observed the heads of the rivet have been flattened and that the contacts 37 and 38 have been made spoon-bowl shaped in order to facilitate the movement of the brush into circuit closing relation with its associated contacts. The breaker being a non-con-

ductor and constructed so that the brush is spaced inwardly from its upper back edge acts as a spark snuffer in either open or closed position, since it shields one contact from the other at all times.

Breaker 32a shown in Fig. 10 is constructed along the same lines as breaker 32 except the brush 36a is different. In the modified showing the brush 36a is bent around the breaker and held in place by an eyelet rivet 35a extending through the bent around parts. The circuit closing means of the brush is offset at its point of riveting, whence it is curved in an edgewise manner to form a somewhat J-shape on each side, the terminal portions 39 and 40 of the arcuate part of the brush being turned toward the breaker to provide for their easy entry between the contacts 37 and 38. This construction provides for somewhat greater flexibility, since after the points 39 and 40 enter between the contacts, the body portion of the J-formations may each yield toward the breaker. The same spark snuffing feature is present in this type of breaker as that already described in breaker 32.

As shown in plan in Fig. 4 and in elevation in Figs. 2 and 3, the side walls 3 and 4 of the casing have formed in their upper portion guideways 41 and 42 into which the switch terminals 43 and 44 are extended thus bringing their respective contacts 37 and 38 into juxtaposition wherein they constitute stationary terminal parts of a knife blade switch wherebetween the brushes 36 and 36a are moved to close an electric circuit. The cooperating notches 45 and 46 on one side of the casing and the cooperating notches 47 and 48 on the opposite side of the casing maintain dependably the placement of the terminals 43 and 44 so that the contacts thereof also maintain their fixed relation. Since terminal 44 spans a wider space than does terminal 43, the terminal 44 is bowed at 49 between the stop pillar 50 and the wall 4 so as to wedge therebetween to stabilize the deflection which carries the contact 38. Into holes 51 and 52, of the terminals 43 and 44 shown in Fig. 8, are screwed the binding screws 53 and 54 whereto the circuit wires are joined.

The means for actuating the breaker 32, whether the switch action be one of snap or delay comprises the swingable cradle 55, the toggle switch lever 56 and the coil spring 57 operatively relating said cradle and lever.

The external portion of the toggle lever 56 is similar to the conventional lever of its type except that the trunnions 58 whereby it is pivotally mounted are positioned eccentrically in relation to said lever. Said trunnions rest in seats formed by notches 59 formed in the front edges of the casing side walls 3 and 4 as shown in Figs. 2 and 3 and are kept in place by the face strap or yoke 15a when the latter is attached to the casing 1 by means of the set screw 15 already mentioned and the attaching screw 15b.

An elongated button 60 operates in a guide passage 61 which extends axially through the toggle lever 56 and which has an enlarged inner end portion 62 located within the bell portion 63 of the toggle lever. Within said enlargement 62 is a workably fitted head 64 which is rigidly connected to the button 60 by means of a stem 65. Said head 64 carries a backward extension 66 having an apertured end portion 67 to which is attached one end portion of the spiral spring 57.

The swingable cradle 55 shown in Fig. 8 and

also in Figs. 2 and 9, is provided with outwardly directed trunnions 68 having bearings within seats formed by the inner ends of the internal grooves 69, see Fig. 3, which are continuations of the notches 59 opening out from the front edges of the side walls of the casing. At its free end said cradle is provided with a cutaway portion 70 extending inwardly part way from one of its side edges and is rounded to produce a striker edge to act upon the breaker whereby to move it from open to closed position and vice versa. When upswung the cradle 55 acts upon the inclined surface 32x of the breaker and when downswung said breaker acts upon the upper edge of the foot portion 32y of the breaker. The relationship of the cradle and breaker is clearly defined in plan in Fig. 9. Said cradle is also provided with an elongated slot 71 which extends at a right angle in the direction of the axis about which it swings, said slot being located near the remaining free edge portion which extends forwardly of the cutaway portion just described and which is also rounded to play against the arclike curvature 25 of the piston stem. The limb 72 of the piston stem occupies the slot 71 during the upward swing of the cradle and the limb 73 of the piston stem occupies the slot 71 during the downward swing of the cradle.

At a point inwardly spaced from the slot 71 the cradle is provided with a seat 74 for the other end of the spring 57.

The actuating means for producing a retarded circuit opening action of the switch, in addition to what cooperating mechanism has already been described, includes a tappet finger 75 carried by the head 64 and extending therefrom at a right angle. Said tappet finger 75 is positioned to act upon a spring resisted slidable engager 76 which, in turn, is positioned to engage the piston stem 20 to place the latter in position to be acted upon by the spring pressed cradle 55.

The slidable engager 76 has a body portion 77, (see Fig. 7), carrying a guide or mounting arm 78, which reciprocates in a guide groove 79 provided for it in the interior face of the wall 4, said groove having a contracted mouth 80 (Fig. 2) which keeps arm 78 in place.

In addition to its mounting arm 78, the engager 76 carries a limb 81 having a laterally deflected push arm 82 which is positioned to act upon the forwardly projecting rise 83 of the piston stem 20 to swing the upper end of the latter backwardly to the full line position of Fig. 1 to cause the bridge 84 of the cradle to be brought from the upper seat 27a into a superjacent relation to the offset seat 27, (see Fig. 7), whereby to produce a delayed switch action. A coil spring 85 mounted upon a seat 85a and having its free end connected to the extension 84a of the limb 81 is utilized to restore the engager to normal position so that when the toggle lever is again actuated, the push arm 82 will be clear of the path in which the piston stem will upwardly travel and the bridge 84 will occupy the seat 27a.

The upper back portion of the stem 20 is provided with a shoulder 86, see Fig. 7, which, as the piston descends, is acted upon by the swell 12 that projects internally from the back wall 5 of the casing to restore the descending piston stem to its forward position, there being a recess 87 in the back wall 5 superadjacent the swell 12 to provide clearance for the shoulder portion 86 incident to its contact with said swell.

The piston stem 20 is secured to the piston 19 at a backward inclination to the axis of the

piston and the piston 19 is mounted in the cylinder 16 at a forward inclination to the axis of said cylinder whereby to facilitate the permanent seating of the bridge 84 in the offset seat 27 and the forward tilting of the piston stem when it contacts the swell 12.

A brief résumé of the assembling of the switch and its operation will now be set forth.

The breaker 32 is first installed by projecting it inwardly into the casing as shown in Fig. 6 by compressing the wings 29 and 30 of its mounting yoke 31 into the acute angle recesses into the position shown in Fig. 3. The terminals 47 and 48 are next mounted in their respective grooves thus bringing the contacts 37 and 38 into juxtaposition as shown in Fig. 4. The piston and dashpot assembly is next swung into position by first positioning the flange 49 in the channel 9 and later applying the screw 15. The cradle is next installed by projecting it forwardly into the casing until its trunnions 68 are seated as shown in Fig. 3. As this operation is being performed the bridge 84 is extended through the gap 26 in the piston stem and the slot 71 is caused to engage the limb 73 of the piston stem. The engager 76 with spring 85 is next installed in the groove 79 with one end of the spring engaging its seat 85a. The toggle assembly including the spring 57, spring hanger 69 and button assembly 60 is then installed with the trunnions 53 of the lever occupying the seats 59, and the free end of the spring 57 mounted upon the seat 74 of the cradle. Finally affixing the remaining well known conventional parts the assembly is completed.

The switch normally is in snap action position, and when manually converted into delay will, upon completion of the delay function, be automatically converted back into a position for snap action movement. This cycle of operation will now be set forth in proper sequence.

In the full line position of the toggle lever in Fig. 1 the switch is in the "on" position. To move it to dotted line position opens the switch. Moving the toggle lever from one stated position to the other may be carried on ad infinitum with a snap action of the switch always resulting. This is accomplished by the striker shoulder 70 of the cradle 55 contacting the breaker 32 under the compressive force of the spring 57. During such movements of the cradle the delay action mechanism remains passive, since the bridge 84 of the cradle moves freely up and down in the cutout in the piston stem, and the slot 71 adjacent to the bridge permits free passage of the limbs 72 and 73 therethrough.

If it is desired to produce a delay action in the circuit opening of the switch the button 60 is pushed inwardly incident to actuating the movement of the toggle lever from the full line to dotted line position. Such movement of the button causes the tappet finger 75 to act upon the engager 76 to move the push finger 75 to act upon the engager to move the push finger against the part 23 of the piston thereby to unseat the bridge 84 in the seat 27a and move it forwardly into the offset seat 27. Such push action having been opposed by the spring 85. The spring 57 now being placed in a state of compression causes the bridge to bear upon its seat and move the piston 19 downwardly in the cylinder 16, such movement being opposed and retarded by the dashpot structure 14. Upon nearing the completion of the downward stroke the shoulder 86 of the piston contacts the cam portion of the swell 12

thereby unseating the bridge 34 from the seat 27 thereby placing the delay action mechanism in a passive condition and automatically restoring the snap action movement of the switch. As soon as the manual pressure upon the button is ceased the spring 35 restores the engager to normal position which position clears the push arm 32 of the path of upward travel of the piston stem. The relationship of the screw 17 and washer 16 may be varied to obtain varied periods of delay action.

What is claimed is:

1. In a snap action switch, a manually controllable mechanism for delaying the snap action, said mechanism including a dashpot furnished with a piston head consisting of rigid disks and an intervening gasket and a piston stem consisting of a metal strip one end portion of which is angularly reduced in width thereby providing a narrowed extension and a shoulder at each side of said extension in an abutting relation to the outer face of said piston head, said extension projecting through said piston head and being angularly deflected upon the inner face of the latter thereby clamping said gasket between said disks, the metal strip which forms said stem having through it along the greater portion of its length, a slot, said slot having an offset portion forming a seat, and a spring pressed part comprising a cradle including a bridge which acts at times against said seat to move said piston against the opposition of the fluid in the dashpot, manually operable means to swing said piston stem to a position wherein the bridge of said cradle is in an engaging relation to said seat, means to automatically swing said stem to its original snap action position at the completion of each movement of the piston into the dashpot, and circuit closing and opening means actuated by said cradle.

2. The subject matter of claim 1 and, said stem having a cut-out providing ingress to said slot, the bridge of said spring pressed part being insertable through said cut-out.

3. In a snap action switch, a casing, a dashpot connected thereto and having a piston furnished with a stem consisting of a strip of rigid material having through it a longitudinal slot, there being a cut-out leading into one side of said slot in a spaced relation to the end thereof which is farthest from the piston, that end portion of the slot having an extension directed toward the same side as said cut-out, thereby forming a seat or shoulder which is directed away from the cut-out, a cradle consisting of a plate having at one end corners each of which is furnished with a trunnion, whereby said cradle is swingably mounted upon said casing, there being a longitudinal slot through the opposite end portion of said cradle, said slot being separated from the free end of the cradle by an intact portion which forms a bridge, the slot through said cradle being sufficiently large to admit the part of the piston stem between its said seat and cut-out, means to manually swing said stem to a position wherein said bridge is in an operative relation to said seat, cam means carried by said casing to engage said stem and restore it to its original position, a spring operatively related to said cradle to swing it against said seat in opposition to said dashpot, thereby to delay the snap action of the switch, and circuit closing and opening means actuated by said cradle.

4. The subject matter of claim 3 and, said cut-out being spaced away from the end of the slot

of said stem which is nearest to the piston head, said spring giving to said cradle a snap action which causes its slotted portion to cross said cut-out and pass astride the material at the opposite side thereof.

5. In a snap action switch, a casing having a wall with a groove the mouth of which is contracted, a fulcrum member having opposite edge portions which fit within the deeper portion of said groove and thus maintain said member in its mounted position, a circuit making and breaking part fulcrumed upon said fulcrum member, electrical contacts associated with said circuit making and breaking part, and means to manually operate said part.

6. The subject matter of claim 5 and, said fulcrum member consisting of a plate having along each of opposite edges a flange, said flanges being deflected away from each other and occupying opposite sides of the bottom part of the groove.

7. In a device of the kind described, a casing, a dashpot structure connected to said casing and including a piston having a stem which is swingable in a plane in which the axis of the dashpot lies, said stem having a longitudinal slot through it, said slot having a lateral recess which forms a seat or shoulder that is directed away from the head of the piston, a swingable part carrying a bridge to engage said seat at times, a spring positioned to act upon said part to press said bridge against said seat and thereby urge said stem toward the dashpot against the opposition of the contents thereof, a slide operable in one direction from its normal position to engage said piston stem and swing it to a position wherein its said seat is engageable by said bridge, a spring positioned to restore said slide to its normal position, cam means carried by the casing to automatically restore said piston stem to its original position during the completion of each downward movement into the dashpot, and circuit closing and opening means actuated by said swingable part.

8. Means for retarding the circuit-opening action of an electric switch comprising, a casing, a dashpot cylinder in the lower portion of said casing, a piston stem having a head operating in said cylinder, said piston stem having through it a longitudinal slot, there being a cut-out leading into one side of said slot in a spaced relation to the end thereof which is farthest from said piston, that end portion of the slot having an extension directed toward the same side as said cut-out thereby forming an offset seat which is directed away from the cut-out, a manually operable toggle lever mounted in said casing in front of said piston stem, a cradle consisting of a plate having at one end corners each of which is furnished with a trunnion whereby said cradle is swingably mounted upon said casing, there being a longitudinal slot through the opposite end portion of said cradle, said slot being separated from the free end of the cradle by an intact portion which forms a bridge, the slot through said cradle being sufficiently large to admit the part of the piston stem between its said seat and cut-out when said bridge is projected through said cut-out into said slot, a spring adjustable by said toggle lever to cause said cradle to move up or else down, means in part carried by said toggle lever and manually movable in relation thereto to swing said piston stem backwardly to a position wherein its aforesaid offset seat is brought into a subjacent relation to said bridge preparatory to the depression of said piston stem by said

bridge, means carried by the casing to automatically swing said piston stem forwardly thereby releasing said bridge from said seat after it has acted upon the latter to depress the piston, and circuit closing and opening means actuated by said cradle.

9. The subject matter of claim 8 and, yieldable means opposing the manual movement of said means carried in part by said toggle lever.

10. The subject matter of claim 8 and, said circuit opening and closing means comprising a breaker consisting mainly of insulating material, electrical terminals provided with spaced apart contacts between which said breaker moves to open and close an electrical circuit, and a brush carried by said breaker to conduct the current from one contact to the other in completing the circuit.

11. In a snap action electric switch having an auxiliary mechanism for manually converting the snap action into a delayed snap action; an electric circuit controlling handle, means for closing and opening an electric circuit by movement of said circuit controlling handle while said auxiliary mechanism is maintained passive in either direction said handle is moved to open and close said circuit, spring opposed means operatively

related to said auxiliary mechanism, and means carried by said handle and operatively related to said spring opposed means to place said auxiliary mechanism into position for operation by the movement of said handle in one of its directional movements.

12. The subject matter of claim 11 and, yieldable means operatively related to said handle carried means and the first recited means to actuate said auxiliary mechanism.

13. In a snap action switch, a manually controllable mechanism for delaying the snap action, said mechanism including a strip of rigid material which is movable both longitudinally and in an edgewise manner, the delay action relating to the longitudinal movement thereof, said strip having through it a longitudinal slot, said strip having a cutout which affords lateral ingress to said slot, said slot having an edge portion which forms a shoulder, means having a bridge to engage and press upon said shoulder against the retarding action of said strip, said bridge portion being insertable through said cutout, and circuit closing and opening means actuated by said means.

EWING L. SHARP.
